UNITED STATES PATENT OFFICE.

DAVID MARCHANT, OF CHICAGO, ILLINOIS, ASSIGNOR OF ONE-HALF TO
JOHN DOLESE AND JASON H. SHEPARD, OF SAME PLACE.

FEED-REGULATOR FOR CRUSHING-MACHINES.

SPECIFICATION forming part of Letters Patent No. 369,117, dated August 30, 1887:

Application filed October 27, 1886. Serial No. 217,347. (No model.)

To all whom it may concern:

Be it known that I, DAVID MARCHANT, a citizen of the United States, residing at Chicago, in the county of Cook and State of Illinois, 5 have invented certain new and useful Improvements in Feed-Regulators for Crushing-Machines; and I do hereby declare the following to be a full, clear, and exact description of the invention, such as will enable others skilled 10 in the art to which it appertains to make and use the same.

My invention relates to a mechanism for aiding or increasing the speed of the automatic gravitating feed-supply of rock, stone, or ore 15 from a hopper into a breaking or crushing machine, and it is specially intended for gyratory rock or stone breakers and ore-crushers of the class illustrated in Letters Patent No. 243,545; and my invention consists in certain 20 constructions and combinations of parts, as will be hereinafter described, and pointed out in the claims.

In the accompanying drawings, Figure 1 is a portion of a gyratory crusher and hopper 25 with my invention applied thereto, the crusher being shown partly in elevation and partly in section, the hopper fully in section, the features of my invention mostly in elevation, and such portions as would tend to hide more important parts broken away. Fig. 2 is a top view of the same. Fig. 3 is a perspective view 30 of the improved platform or frame, and Figs. 4 and 5 are views showing modified forms of the frames or platforms in cross-section.

The letter A in the drawings represents a 35 gyratory stone-crusher, for which class of crushers my invention, as before mentioned, is peculiarly adapted, owing to the very great speed at which such crushers are operated.

B is a conical hopper. C is an agitating sliding platform or frame, and D a mechanism for moving the same upward and outward, as will be shown.

The crusher, (provided with the hopper,) 45 when set up and ready for use at the quarry-works, is located in the usual way in respect to the dumping-platform, which is either on a level with the top portion of the hopper when the stone is supplied by means of wagons, or 50 at a suitable distance above said top portion when the supply is furnished in railway-earns.

The platform or frame C may consist of two longitudinal bars, c, having cross-bars c', provided at suitable distances, and may have an angularly turned-up or hooking portion, c², 55 and may be strengthened by two angular bars, c³, fastened to the under sides of the frame-bars c, and the turned-up ends of the bars c² facing the center of the crusher. The outer end portion of the platform or frame C is provided with a draft-rod, c⁴, by means of which it is moved, as will be apparent. A rope or chain, E, is fastened to an eye, c⁵, at the end of the rod c⁴, which rope or chain passes over two pulleys, e e', and has a weight, E', suspended at its end. The pulleys e e' are suitably hung to the frame-work of the dumping-platform above mentioned, and the pulley e is set back of the eye c⁵ of the slide C, or between it and the center of the crusher, so that the 60 weight E' tends to force the platform or frame 65 toward the center of the crusher. Another cord, F, is fastened to the eye c⁵, and runs over a guide-pulley, f, and to a drum, G, of the mechanism D, by which drum it is slowly 70 wound up, as will be apparent. 75

The drum G is properly hung in an auxiliary frame, g, or otherwise, and is provided with a cog-wheel, g', Fig. 2, which is revolved by a pinion, g², connected with a pulley, g³, on 80 the said frame g. The pulley g³ is revolved by means of a belt, g⁴, which receives its motion from a small pulley, a, on the counter-shaft a' of the crusher A. By this construction the drum G and platform or frame C receive 85 a very slow motion, and thus the platform or frame is moved fully up to the outer or upper rim of the hopper during one feeding period.

When nearly all or all of the stone has been 90 discharged into the crusher below, the frame or platform will have arrived at the termination of its upward and outward movement. If any portion of stone is still on the platform or frame, it may be discharged by turning the platform edgewise by hand. As soon as the 95 frame or platform has completed its aforesaid movement, the belt g⁴ is thrown off by hand the pulley g³, and thereupon the weight E' pulls the frame or platform C down toward the upper central bearing, a³, of the crusher. 100 In doing this the weight E' sets the drum G, the wheels g'g², and pulley g³ in motion, thereby

unwinding the rope F from the drum, while the motion of the platform or frame is slackened to a proper speed; and when the platform or frame approaches the bearing a^3 as closely as is safe the attendant can, by putting his hand upon the pulley g^3 , in lieu of a brake, stop the motion of the platform or frame C, and thereby prevent a concussion between it and the bearing a^3 . A fresh supply of stone 10 is then dumped into the hopper, the belt g^4 is again thrown over the pulleys g^3 and a^4 , and the platform or frame C is again set in motion. While the platform or frame slowly passes through the stones heaped above it, and while 15 the stones are constantly passing down right and left into the crusher, the formation of bridges over the apertures a^2 by the slowly-sinking stones is prevented, inasmuch as the hook or upright portion c^2 is continually making its way in a central direction through the place at which such bridges would form, and is thus continually displacing the keystones of such bridge formations, and thereby keeping the surrounding stones disconnected and 20 free to drop down into the crusher.

The stone-crushers of this class have generally a plurality of—or commonly three—apertures or feed-openings, a^2 , around the upper center bearing, a^3 , and for each aperture a 25 platform or frame, C, is used. All of the platforms or frames are of the construction described. They are each provided in the aforesaid manner with back-acting weights E'; but their ropes F' are fastened to the above-described drum G, as shown. In order to render said connecting-ropes F' operative, they are held by means of guide-pulleys f' in such positions that they incline to drum G and platform C in the directions requisite for correct operation, similar to that before described.

It will be seen that while all the platforms are alike and move outwardly from the center in the same manner, the devices for moving two of the three are combined with the devices 45 by which the first one is moved in a novel manner, so that all of the frames move simultaneously both outward and inward. It is desirable to employ several platforms or frames upon the inclined wall of the hopper and 50 around the center bearing portion, a^3 , of the circular bottom thereof, for by this construction the mass of stone around said center bearing of the circular bottom of said hopper is disturbed at different points simultaneously, 55 and the liability of the stones becoming locked upon one another at any one point, so as to form bridges or arches, is greatly lessened.

In Figs. 4 and 5 are shown modified forms of the agitating sliding platforms or frames C. (Shown in the other views.) The said platforms or frames in these views present, in their cross-section, the form of an arch and of a gable roof, and the abutments of the arch are in form of narrow bars, as c. By this construction the platforms or frames offer but slight frictional contact with the bottom of the hopper, and stones falling upon the plat-

forms or frames glide off laterally, and smaller pieces of stone, passing through the open bottoms of the platforms, can roll down to the receiving feed-openings beneath the arched platforms or frames, while pieces of stone can also pass through the spaces at the inner ends of the platforms or frames.

The platforms or frames can be provided 75 with strong vertical separated projections or pins n (see Fig. 4) in lieu of the inner end cross-bars and angular or turned-up end portions, c^2 c^3 , said pins being upright projections from the lower arched cross-bar c' (shown 80 in Fig. 4) and not united at their upper ends, as in Fig. 5.

What I claim as my invention is—

1. The combination, with the crusher having a hopper with inclined wall and a circular bottom with feed-opening, of the platform or frame C, resting loosely on said inclined wall, and operating mechanical devices, constructed and arranged as described, whereby it can be moved continuously outward while feed is in the hopper and during the crushing operation, substantially as described.

2. The combination, with the crusher having a hopper with inclined wall and a circular bottom with feed-opening, of the platform or frame C, resting loosely on said inclined wall, and operating mechanical devices, constructed and arranged as described, whereby it can be moved continuously outward while feed is in the hopper and during the crushing operation and then be moved continuously inward to its starting position, substantially as described.

3. The combination, with the crusher having a hopper with inclined wall and a circular bottom with feed-opening, of the platform or frame C, resting loosely on said inclined wall and provided with a draft-rod, c', and an eye, c'', and mechanical devices, constructed and arranged as described, whereby it can be moved continuously outward while feed is in the hopper and during the crushing operation, then continuously returned to its starting position, substantially as described.

4. The combination, with a circular crusher 115 and a hopper having a plurality of feed-openings, of a plurality of feed-regulating platforms or frames and mechanical devices whereby said frames are connected and simultaneously moved outward continuously while feed is in the hopper during the crushing operation, substantially as and for the purpose described.

5. The combination, with a crusher and a hopper having an inclined wall and feed-opening, of a feed-regulating platform or frame loosely resting on the inclined wall of said hopper, and having the upright portion c^2 at its lower end and horizontal portion c, and mechanical devices whereby said frame is 130 moved outward continuously while feed is in the hopper and during the crushing operation, substantially as described.

6. The combination, with the hopper, of the

platform or frame C, comprising frame portions c , with upright or hooked portions c^1 and arched cross-bars c^2 , applied loosely on the bottom of the hopper of the stone-crusher and 5 connected with mechanical devices by which it is moved outward continuously while feed is in the hopper and during the crushing operation, and inward to its starting position after the contents of the hopper are emptied, 10 substantially as and for the purpose described.

7. The combination, with the hopper of a stone-crusher, of the platform or frame C, chain E, suitable guide-pulleys, weight E', chain F, drum G, and means for operating said drum, 15 substantially as and for the purpose described.

8. In combination with the hopper of a stone-crusher, the platform or frame C, chain F, drum G, driving-pulley a , and suitable

connections between the driving-pulley a and drum G, gear-wheels g^1 g^2 , pulley g^3 , and belt 20 g^4 , substantially as and for the purpose described.

9. The combination, with the hopper, of the feed-regulating platform resting loosely thereon and having the vertical portion c^3 , and 25 movable outward from the center to the periphery of the hopper for freeing the stone in the hopper, the stone-crusher, and hopper having a feed-opening, substantially as described. 30

In testimony whereof I affix my signature in presence of two witnesses.

DAVID MARCHANT.
